UNITED STATES PATENT OFFICE.

OSCAR HAYES, OF DENVER, COLORADO.

VALVE-CONTROL DEVICE.

1,425,088.

Specification of Letters Patent. Patented Aug. 8, 1922.

Application filed August 14, 1918. Serial No. 249,763.

To all whom it may concern:

Be it known that I, OSCAR HAYES, a citizen of the United States, residing at Denver, in the county of Denver and State of Colorado, have invented certain new and useful Improvements in Valve-Control Devices, of which the following is a specification, reference being had therein to the accompanying drawing.

10 This invention relates to an improved air control device, and more particularly to a device of this character adapted to be operatively connected to the intake manifold of internal combustion engines for motor driven vehicles, whereby to add to the gaseous mixture as admitted to or passing through, the manifold, an additional supply of air, and which said supply may be conveniently and accurately regulated or entirely shut off at will.

15 It is a matter of common knowledge that when an engine is cold, as on starting, a richer mixture is desirable, whereas after the engine becomes heated far better results are obtainable, to say nothing of the saving of gas, by a lighter mixture, and with this in view compensating valves of various types and designs have heretofore been extensively employed to regulate the gaseous 20 mixture after it has left the carburetor by adding to said mixture a direct supply of air. Most of these prior constructions with which I am familiar have proven satisfactory for their intended purposes to a large 25 extent, but it has been ascertained in practice that after some considerable use, especially when pivotally connected parts are relied upon, the parts tend to become bent, broken, dislocated, or will stick, with the 30 result that they fail to function properly, and it is one of the objects of the present invention to provide a compensating valve more positive and direct in operation, than prior similar valves, and otherwise over- 35 coming existing difficulties and defects, and at the same time making possible a valve of the type under consideration neat in design and construction, including a minimum number of parts and hence simple and cheap 40 to produce, while at the same time highly efficient and satisfactory in use.

45 In carrying out the invention it is proposed to provide a valve proper mounted for bodily movement and directly actuated by a connected operating part, and adapted 50 in its movement to accurately regulate the

quantity of air discharged from the there-with associated enclosing casing to the manifold of the engine.

55 It is a further object of the invention to provide an improved compensating valve of the character under consideration readily applicable to manifolds of various designs and constructions, and adapted to be operated from the dash board of the car in which the engine is mounted.

60 It is further contemplated by the invention to provide a valve construction which while primarily designed to regulate an auxiliary supply of air to the manifold, may 70 with equally satisfactory results be utilized for supplying variable quantities of gas directly to the manifold for priming purposes in starting the engine.

65 More particularly the invention includes 75 a valve casing adapted to be mounted on a suitable support, as the dash board, the casing having an inlet port and a discharge outlet or conduit adapted to be connected to the intake manifold or other part of the 80 engine, and a bodily movable valve within the casing adapted to be actuated conveniently by a fixed connection with the valve extending without the casing, thereby regulating, according to the position of the 85 valve, the air or gas as the case may be emitting from said discharge conduit.

70 The invention also includes means whereby the valve may be effectively locked in adjusted positions against displacement under 90 vibration, etc., which said locking characteristic is however automatically releasable under pressure when it is desired to adjust the valve.

75 Still other and further improvements, 95 and novel details in the construction and arrangement of parts will be appreciated from the description to follow, when considered in connection with the accompanying drawings, which form a part hereof, 100 and wherein is disclosed, for the purposes of illustration, a convenient and satisfactory embodiment of the invention, it being borne in mind in this connection that various minor changes may be resorted to without departing from the spirit of the invention.

80 In the drawings,

85 Figure 1 is a plan view of the improved device applied to a dash board and manifold, the latter parts being broken away. 110

90 Figure 2 is a longitudinal section of the valve mechanism proper.

Figures 3, 4, and 5 are sectional views taken on lines 3—3, 4—4 and 5—5, respectively, of Fig. 2.

With more particular reference to the drawings, wherein like reference numerals refer to corresponding parts throughout the several views, 1, is a diagrammatic representation of an intake manifold of an internal combustion engine of any approved type, 10 and 2 a similar representation of the dash board of a motor vehicle, these parts being broken away, in that in detail they constitute no part of the present invention. 3 is a valve casing, conveniently elongated 15 and round in cross section, though the same may take various forms of tubular outline. Projecting from the peripheral wall of the valve casing is a suitable projection which in the illustrative embodiment of the invention extends upwardly and at an incline to the transverse axis of the casing. This extension which may be cast integral with the casing constitutes a supporting bracket and is apertured whereby to receive screws or other fastening means which engage one face of the dash board 2, as illustrated at 4. In this connection, however, it is within the contemplation of the invention to, if desired in some instances, apply 25 the casing directly to the manifold or like, and to this end the outlet end of the casing is reduced, and threaded at 5 whereby to engage a similarly threaded aperture in the manifold. In the preferred embodiment of 30 the invention wherein the valve casing is mounted on the dash board, a discharge conduit is provided conveniently as illustrated at 6, and a suitable coupling member 7 of any approved type threaded to the 35 threaded portion 5 of the casing serves to retain the conduit detachably in place. The conduit may and preferably does connect with a plurality of branches 8 which latter in turn connect at any convenient point 40 to obtain best results with the intake manifold 1, apertures being provided in the latter for the reception of the terminals of the branches 8. The casing 3 is provided with an inlet port 9 in the upper surface thereof 45 and an outlet aperture 10 in the end thereof. The valve proper conveniently takes the form of a plurality of disks, four being shown for purposes of illustration at 11, 12, 13 and 14 respectively, though the number 50 may be varied according to the degree of adjustment desired. The said disks are mounted upon and may be integral with a stem which projects rearwardly through the rear end of the casing and terminates in a hand engaging or actuating part such as a knob 16, the stem being represented at 55. The rear end of the casing preferably takes the form of a removable cap suitably threaded to the body portion of the casing 60 and apertured for the loose reception of 65

the stem 15. This cap constitutes a stop for limiting the outward sliding movement of the valve. The passage of air from the inlet port 9 through the outlet 10 is controlled by the particular position of the valve disks 11, 12, 13, 14, in the casing 3, and to this end the disks 12, 13, 14 are provided with portage of gradually increasing area. A preferable way of accomplishing the result is to provide the disk 12 say with 70 one aperture 12^a, the disk 13 with two apertures 13^a, and the disk 14 with say four apertures 14^a. The disk 11 is preferably solid so that when the same assumes a position forwardly of the intake port the air 75 will be entirely shut off from the discharge port, and to facilitate this result the disk 14 preferably connects with a conical terminal 17 shaped to snugly fit in a similarly formed seat 18 on the interior wall of the 80 front end of the casing which surrounds the outlet port 10.

From the description thus far, it will be appreciated that as the operator grasps the knob 16 and slides the valve rearwardly to a 90 point where the disk 11 is positioned rearwardly of the intake aperture 9 and the disk 12 is positioned forwardly of such aperture, the amount of air fed through the casing and discharged from the outlet 10 will be determined by the size of the single aperture 95 12^a in said disk 12, whereas a continued rearward movement of the valve will register the disks 13 and 14 in succession with the inlet port, thereby increasing the air passage to 100 the desired extent.

It is desirable of course to maintain the valve in adjusted position, and a very satisfactory and efficient means for this purpose takes the form of a member 18^a, conveniently 105 a ball of a size to engage over the walls of the disks and between adjacent disks, the ball 18^a being held in locking position by a suitable spring support 19 positioned in a seat formed by a hollow projection on the under surface of the casing 3, the projection being illustrated at 20. While the spring held locking means is sufficient to maintain the parts in fixed position at all 110 times under normal conditions, at the same time the same is automatically releasable when manual pressure is applied to the operating knob 16, and on the other hand the same will automatically seat between the disks or to the rear side of the rearmost disk 11 in the valve adjusting movement.

While the present attachment is more especially designed for the regulation of air to the intake manifold, at the same time, without any change whatsoever it is equally servable for the priming of the engine, the gas being admitted through the inlet port 9, and because of the downward inclination of the casing will readily flow through the casing and along the conduit 6, branches 7, and 125 130

find an exit directly in the manifold, whereby a rich mixture of gas will be directly delivered at the most desirable point to obtain ease in starting the motor.

5. What I claim is:

1. A valve control device of the character described comprising a valve casing having an inlet and an outlet, the latter being adapted to be connected with an engine part such as the intake manifold, and a bodily movable valve in the casing provided with a plurality of variably ported disks adapted to be positioned between the inlet and the outlet of the casing for regulating the supply of fluid through said outlet, and actuating means directly connected to the valve and projecting without the casing.

2. A valve control device of the character described, comprising a valve casing having an inlet and an outlet, the latter being adapted for connection with the intake manifold of an engine, a slideable valve in the casing provided with a variably ported plural disk head, said disks being adapted to be optionally positioned between the inlet and the outlet of the casing, and a manually operable actuating stem projecting from the valve and extending without the casing and adapted to be moved back and forth to regulate the amount of fluid passing through the casing.

3. A valve control device adapted to be operably connected to the intake manifold of an engine, comprising a valve casing having supporting means for connection to a dash board of a motor vehicle, said casing having an inlet and an outlet, a slideable valve provided with a series of variably ported disks each of said disks adapted to be optionally positioned between the inlet and the outlet of the casing for controlling according to its position in the casing the quantity of fluid discharging from the outlet, said valve having an extended stem portion projecting through one end of the casing, and a hand operating part on said projecting end of the stem.

4. A valve control device adapted to be operatively connected with the intake manifold of an engine, comprising a valve casing having supporting means whereby to secure the casing at an inclination on the dash board of a motor vehicle, said casing having an inlet at a point removed from the lower end thereof and an outlet adjacent said lower end, means for connecting said lower end with the manifold, and a manually operable slideable valve in the casing provided with a plurality of variably ported disks each of said disks adapted to be optionally positioned between the inlet and the outlet of the casing whereby to regulate the amount of fluid discharged from the outlet.

5. A valve control device adapted to be operatively connected to the intake mani-

fold or the like of engines, comprising a tubular casing, means for supporting the casing at an inclination, said casing having an inlet for air or gas at a point removed from the lower end thereof and an outlet adjacent the lower end thereof, and a slideable valve in the casing provided with a series of disks each having a portage of differing area and adapted to be optionally positioned between the inlet and the outlet of the casing for governing the control of fluid from the inlet through the outlet.

6. A valve control device adapted to be operatively connected to the intake manifold of engines, comprising a tubular valve casing having an inlet and an outlet, a slideable valve in the casing provided with a plurality of disks each having a portage of differing area and arranged according to its position in the casing to variably restrict the discharge of fluid through the outlet, and means within the casing for maintaining the valve in adjusted positions.

7. A valve control device of the character described comprising a valve casing having an inlet and an outlet, the latter being adapted to be connected with an engine part such as the intake manifold, a valve in the casing provided with a plurality of disks, each of said disks having a portage of differing area, and means for moving the valve to position any of the disks between the inlet and the outlet of the casing for regulating the supply of fluid therethrough.

8. A valve control device of the character described comprising a valve casing having an inlet and an outlet, the latter being adapted to be connected with an engine part such as the intake manifold, a valve in the casing provided with a series of disks each having a portage of differing area therethrough, and means for bodily moving the valve to position any of said disks between the inlet and the outlet of the casing for regulating the supply of fluid through the outlet.

9. A valve control device adapted to be operatively connected to the intake manifold of an engine, comprising a valve casing having an inlet and an outlet, a valve in the casing provided with a plurality of disks, each of said disks having a portage of differing area, and means for moving the valve to position any of the disks between the inlet and the outlet of the casing for regulating the supply of fluid through the outlet.

10. A valve control device of the character described comprising a valve casing having an inlet and an outlet, the latter being adapted to be connected with an engine part such as the intake manifold, a bodily movable valve in the casing having a series of disks provided with progressively increased ported areas therethrough, each of said disks being adapted to be positioned between the

inlet and outlet of the casing for regulating the supply of fluid through the outlet, and actuating means connected to the valve.

11. A valve control device of the character described comprising a valve casing having an inlet and an outlet, the latter being adapted to be connected with an engine part such as the intake manifold, a valve in the casing having a plurality of disks, each of 10 said disks being provided with a portage of

differing areas, and means for moving the valve to position any of the disks between the inlet and outlet of the casing for regulating the supply of fluid therethrough.

In testimony whereof I hereunto affix my 15
signature in the presence of two witnesses.

OSCAR HAYES.
